SPECTACLE FRAME

Andrew Havas, New York, N. Y.

Application May 22, 1952, Serial No. 19,841

Term of patent 3½ years

(Cl. D57—1)

To all whom it may concern:

Be it known that Andrew Havas, a citizen of the United States of America and resident of the city, county, and State of New York, has invented a new, original, and ornamental Design for Spectacle Frame, of which the following is a specification, reference being had to the accompanying drawing, forming part thereof, in which

Fig. 1 is a front elevational view of a spectacle frame embodying my new design;

Fig. 2 is a side elevational view thereof, the opposite sides being identical;

Fig. 3 is a cross sectional view taken substantially along the line 3—3 of Figure 1; and

Fig. 4 is a cross-sectional view taken substantially along the line 4—4 of Figure 2.

The dominant features of my design are shown in solid lines.

I claim:

The ornamental design for a spectacle frame, substantially as shown and described.

ANDREW HAVAS.
